PLUG-TYPE LAG FUSE

Leonard N. Baenziger, Pawtucket, R. I., assignor
to Royal Electric Company, Inc., Pawtucket,
R. I., a corporation of Rhode Island

Application May 1, 1952, Serial No. 285,371

3 Claims. (Cl. 200—123)

1

This invention relates to plug-type lag fuses, and is an improvement on the lag fuse disclosed in my Patent No. 2,557,587, dated June 19, 1951.

The principal purpose of the present invention is to provide an improved plug fuse of conventional exterior form but equipped with a fuse link having heat absorbing bodies of predetermined and substantially equal mass disposed on opposite sides of the neck or fusible portion of the link, whereby the heat caused by a moderate and brief overload will be dissipated without melting the fusible link, yet the fuse will blow under a sustained overload or a short circuit.

The fuse of my prior patent operates with general satisfaction in performing the same purpose, but the formation of heat-absorbing solder pockets by coiling a continuous fuse strip upon itself does not ensure accurately predetermined masses and uniform blowing time under overloads of the circuit. Hence, in accordance with this improvement, the pockets for the solder masses are accurately and uniformly produced by bending the fuse link in dies to provide a pair of preformed pockets of similar shape, each of which will hold a predetermined mass of heat-absorbing material. The fuses thus made will accordingly exhibit a uniform time delay period under temporary and moderately overloads.

A further object of this invention is to provide a fuse link composed of two metals of different conductivity whereby a relatively high resistance and low melting point metal such as zinc may be used for the fusible leg of the composite strip, and a metal of lower electrical resistance, such as brass, may be used for the other leg, to prolong the time lag before the link blows. Thus, the overload rating of the improved fuse may be regulated by varying the thickness of either or both legs, while maintaining constant the total mass of heat-absorbing solder plugs formed in the respective legs.

A preferred embodiment of the invention is illustrated in the accompanying drawings, in which:

Fig. 1 is a plan view of the improved lag fuse, partly broken away and in section;

Fig. 2 is a section on line 2—2 of Fig. 1; and Fig. 3 is an edge view of the respective legs of the fuse link, with the solder pockets formed therein, and with the legs associated in operative relation.

In the particular form chosen for the purpose of illustration, the plug-type lag fuse comprises the usual body 11 of insulating material, a conventional top part or cover 12 of glass or the

2

like, and a standard, threaded metal shell 13 which holds the body and cover in assembled relation and which constitutes a conductor when the plug is screwed into a conventional socket.

5 The base terminal 14 is riveted in the exposed end of the body 11 in the customary manner. The structural details of these parts of the fuse are not material to this invention, and may be varied as desired.

10 In accordance with this invention, the improved fuse link preferably consists of a zinc strip or leg 15 wrapped around the end of the tubular portion 16 of the cover 12 and having one end soldered at 17 to the shell 13; and a brass strip or leg 18 soldered or otherwise attached at one end to the terminal 14. The opposite end portion of the zinc leg 15 is bent to form a substantially rectangular, open-sided pocket 19, and may be further bent at 20 to provide a narrow fusible neck 21 disposed approximately at the transverse center of the fuse cavity. The extremity 22 of leg 15 is attached to the brass leg 18 as explained below.

15 The opposite end of the brass strip 18 is bent to form a three-sided, substantially rectangular pocket 23 of a size approximately corresponding to the pocket 19. The extreme end 22 of the zinc leg is mechanically and electrically connected to the extremity 24 of the brass leg, and 20 may extend outwardly to close the pocket 23, as shown in Fig. 2.

25 It is not essential that the pockets 19 and 23 be identical in size, but the two pockets are accurately formed, preferably by dies, to ensure 30 that the total capacity of both pockets may be predetermined. These pockets receive a mass of heat-absorbing material, preferably solder which hardens in the respective pockets 19 and 23 as solder plugs 25 and 26. Plug 26 serves as the connecting means between leg ends 22 and 24. By 35 forming the pockets as just described, the total mass of the two lugs will be uniform in every lag fuse produced pursuant to this invention.

40 It will be apparent that the solder plugs will absorb and dissipate the heat of a quick surge of current caused by a moderate overload, so that the fusible neck 21 will not melt under such conditions; but that the fuse link will blow in case of a sustained or heavy overload, or of a short circuit. It will also be understood that the operating overload time may be regulated, in part, by varying the thickness of either or both of the fuse strips 15 and 18, while maintaining 45 the same width thereof and also maintaining the

same capacity of the respective solder pockets 19 and 23.

I claim:

1. A plug-type lag fuse comprising a fuse link composed of two metal strips of differing melting points means electrically connecting said strips together in series, each strip having a three-sided pocket of predetermined capacity formed therein, the strip of lower melting point having a fusible portion, and solder plugs of size corresponding to the capacities of the respective pockets received and held in the respective pockets.

2. A plug-type lag fuse comprising a fuse link composed of two metal strips of differing melting points means electrically connecting said strips together in series, each strip having a three-sided pocket of predetermined capacity formed therein, the strip of lower melting point having a fusible portion, and solder plugs of size corresponding to the capacities of the respective pockets received and held in the respective pockets, one end of said fusible strip closing the open end of the pocket in the other strip and being connected to said other strip by the solder in 25 said pocket.

3. A plug-type lag fuse comprising: a metal strip of predetermined melting point, having a U-shaped bend forming a pocket of predetermined capacity, an extending straight leg and a fusible portion disposed between said bend and said leg; a second metal strip of higher melting point than the first, also having a U-shaped bend forming a second pocket of predetermined capacity; said leg being disposed to close the open end of said second pocket; and solder plugs of size corresponding to the capacities of the respective pockets, received and held in the respective pockets, the plug in said second pocket being connected to said leg and forming an electrical connection between said strips.
